UNITED STATES PATENT OFFICE.

CARL HOWARD FLINT, OF NEW YORK, N. Y.

HULL FOR HYDROAEROPLANES.

1,110,918.

Specification of Letters Patent. Patented Sept. 15, 1914.

Application filed May 17, 1913, Serial No. 768,253. Renewed July 24, 1914. Serial No. 352,933.

To all whom it may concern:

Be it known that I, CARL HOWARD FLINT, a citizen of the United States, and a resident of the city of New York, borough of Brooklyn, in the county of Kings and State of New York, have invented a new and Improved Hull for Hydroaeroplanes, of which the following is a full, clear, and exact description.

10 This invention relates to hydro-aeroplanes, and more particularly to a hull for such amphibious crafts. In hydroaeroplanes as at present constructed it is common practice to construct the body of the machine as a 15 float with floats applied to the ends of the wings or lifting planes in order to give the required stability, or the aeroplane is mounted upon catamaran floats to provide for the lateral balance of the floating machine. These two types of construction are 20 objectionable, especially when traveling in rough water, and furthermore the maneuvering of the machine is difficult under some conditions.

25 The general objects of the present invention are to provide a floating hull for a hydro-aeroplane which is of such a construction that it has great flotation power, offers comparatively little resistance when traveling in the water, is easy to steer and possesses great stability, and furthermore in flight it has a lifting power of its own. In accomplishing these results the hull is constructed without a central keel but has extending along its bottom adjacent the sides 30 longitudinally extending fins which are suitably spaced apart to form between them a channel, and the top of this channel is formed with a series of forwardly and upwardly inclined planes arranged in stepped relation, whereby considerable buoyancy in the water is obtained, as well as a great lifting power due to the air impinging on the inclined surfaces, the air being confined by 35 the said fins in a manner to maintain a decided lifting effect, this being true both when the craft is traveling in the water or flying through the air.

With these objects in view, and others as 40 will appear as the description proceeds, the invention comprises various novel features of construction and arrangement of parts which will be more fully described herein-after and set forth with particularity in the 45 claims appended hereto.

In the accompanying drawings, which illustrate one embodiment of the invention, and wherein similar reference characters are employed to designate corresponding parts throughout the several views, Figure 1 is 50 a bottom plan view of the hull; Fig. 2 is a longitudinal section thereof; and Fig. 3 is a transverse section on the line 3—3 of Fig. 2.

Referring to the drawing, 1 designates the 55 bow of the hull, which is pointed or otherwise shaped to offer comparatively little air resistance in flight, and the stern 2 is flat on its bottom so as to thereby reduce the submerging effect as the hull is lifted at the 60 bow by the raising effect of the air.

Between the bow and stern the hull is formed at its sides 6 with longitudinally extending fins 3 which are comparatively narrow and deep so as to provide between them 75 a comparatively wide channel into which the air enters at the front to have a lifting effect on the hull, the bottom of the hull between the fins 3 being formed into a plurality of inclined planes or surfaces 4. Any 80 number of these planes may be employed according to the length of the hull, three being shown in the present instance as illustrating the plural arrangement. The lower ends of these planes are practically on a 85 common line, and between the lower end of one plane and the upper end of an adjacent plane is a reentrant pocket or chamber 5 whereby the air space under the hull is increased, so as to augment the buoyancy of 90 the hull when it is in the water. The pockets and inclined planes are located wholly above the fins 3, whereby a relatively deep channel is formed under the hull.

As the boat is propelled by its propelling 95 mechanism the air acting in the channel between the fins 3 and on the planes produces a decided lifting effect on the hull, while the propelling speed is below a certain point, and this lifting effect greatly reduces the 100 resistance offered by the hull in traversing the water, but as the speed of propulsion is increased and the elevating means of the air craft is adjusted the hydro-aeroplane rises from the surface of the water and flies as 105 an aeroplane, and the air striking on the planes 4 contributes materially in the lifting and sustentation of the craft. A hull constructed in the manner described possesses great stability, so that catamaran floats or 110

floats on the main planes are unnecessary, and furthermore the structure is such that it will withstand shocks in landing.

From the foregoing description taken in connection with the accompanying drawings, the advantages of the method of operation and of the structure shown will be readily understood by those skilled in the art to which the invention appertains, and while 10 I have described the structure which I now consider to be the best embodiment thereof, I desire to have it understood that the structure shown is merely illustrative, and that such changes may be made when desired as 15 are within the scope of the appended claims.

Having thus described my invention I claim as new and desire to secure by Letters Patent:

1. A hull for hydro-aeroplanes comprising a body formed with longitudinally extending fins at its bottom and a plurality of inclined planes arranged one behind the other and disposed between said fins for producing a lifting effect in transit through the

air and water, there being reentrant pockets 25 between the upper portion of each plane and the lower portion of the adjacent preceding plane, said fins being located entirely below the pockets.

2. A hull for hydro-aeroplanes comprising a body having a pointed bow, a flat stern, fins extending longitudinally of the body at the sides thereof, and a plurality of inclined planes forming the bottom of the body between the fins, said inclined planes disposed one behind the other and the upper end of each plane being shaped to form with the lower end of the adjacent plane a reentrant pocket, said fins being located entirely below said planes and pockets. 40

In testimony whereof I have signed my name to this specification in the presence of two subscribing witnesses.

CARL HOWARD FLINT.
